[57] CLAIM

The ornamental design for a ratchet tap wrench, as shown and described.

DESCRIPTION

FIG. 1 is a disassembled front elevational view of the ratchet tap wrench of the present invention;

FIG. 2 is a disassembled rear elevational view of the ratchet tap wrench of FIG. 1;

FIG. 3 is a disassembled left side elevational view of the ratchet tap wrench of FIG. 1;

FIG. 4 is a disassembled right side elevational view of the ratchet tap wrench of FIG. 1;

FIG. 5 is a disassembled top plan view of the ratchet tap wrench of FIG. 1;

FIG. 6 is a disassembled bottom plan view of the ratchet tap wrench of FIG. 1; and,

FIG. 7 is an assembled front elevational view of the ratchet tap wrench of FIG. 1.

The ratchet tap wrench is shown disassembled in FIGS. 1-6 for clarity of illustration.
